(57) **CLAIM**

The ornamental design for a dental guard, as shown and described.

DESCRIPTION

FIG. 1 is a top perspective view of a dental guard in accordance with one embodiment.

FIG. 2 is a bottom perspective view of the dental guard in accordance with one embodiment.

FIG. 3 is a top view of the dental guard in accordance with one embodiment.

FIG. 4 is a side view of the dental guard in accordance with one embodiment.

FIG. 5 is a front view of the dental guard in accordance with one embodiment.

FIG. 6 is back view of the dental guard in accordance with one embodiment.

FIG. 7 is a bottom view of the dental guard in accordance with one embodiment.

FIG. 8 is an exploded view of the dental guard in accordance with one embodiment.

FIG. 9 is a close-up view of the structure of the third and fourth layers from the top in FIG. 8 and which extends throughout the entire surface of those third and fourth layers; and,

FIG. 10 is a close-up view of the structure of the second layer from the top in FIG. 8.

The broken lines in the drawing illustrate portions of the dental guard and form no part of the claimed design. The broken lines are directed to environment and are for illustrative purposes.

1 Claim, 5 Drawing Sheets
